UNITED STATES PATENT OFFICE

WALTER R. SCHLAGE, OF SAN FRANCISCO, CALIFORNIA, ASSIGNOR TO SCHLAGE
LOCK CO., OF SAN FRANCISCO, CALIFORNIA, A CORPORATION OF CALIFORNIA

DESIGN FOR A FRONT-DOOR-HANDLE PLATE

Application filed December 6, 1929. Serial No. 33,676. Term of patent 14 years.

To all whom it may concern:

Be it known that I, WALTER R. SCHLAGE, a citizen of the United States, residing at the city and county of San Francisco, State of California, have invented a new, original, and ornamental Design for Front-Door-Handle Plate, of which the following is a specification, reference being had to the accompanying drawings, forming part thereof.

I claim:
The ornamental design for a front door handle plate, substantially as shown.

WALTER R. SCHLAGE.
